UNITED STATES PATENT OFFICE.

GEORGE W. BERRY, OF BANGOR, MAINE.

HEEL ATTACHMENT.

1,286,209.

Specification of Letters Patent.

Patented Dec. 3, 1918.

Application filed May 13, 1918. Serial No. 234,251.

To all whom it may concern:

Be it known that I, GEORGE W. BERRY, a citizen of the United States, residing at Bangor, in the county of Penobscot and 5 State of Maine, have invented certain new and useful Improvements in Heel Attachments; and I do declare the following to be a full, clear, and exact description of the invention, such as will enable others skilled in 10 the art to which it appertains to make and use the same.

This invention relates to heel attachments, and it relates more particularly to an improved self securing attachment for a shoe 15 heel of ordinary construction.

One of the objects of this invention is to provide an attachment of this character which automatically engages the heel of a shoe when the latter is placed on the heel- 20 plate of the attachment.

Another object is to provide a device of this character which is easily detached by a single and simple movement of a lever by means of a hand or foot of the user.

25 Another object is to provide a device of this character which is useful either as an ice-creeper or skate-clamp.

Another object is to provide a device of this character which is strong, durable, safe 30 and thoroughly practical.

And another object is to provide a device of this character which consists of few and simple parts and may be manufactured at a low cost.

35 Other objects and advantages may become apparent to persons who read the following details of description in connection with the accompanying drawings, in which:

Figure 1 is a side elevation of a heel attachment constructed in accordance with 40 this invention and attached to the heel of a shoe;

Fig. 2 is an enlarged vertical sectional view substantially along the line 2—2 of 45 Fig. 3;

Fig. 3 is an enlarged vertical sectional view substantially along the line 3—3 of Fig. 2;

Fig. 4 is a view similar to Fig. 2, but showing the parts in a different full line position and in a broken line position;

Fig. 5 is a view similar to Fig. 3, except that it shows the parts in the positions shown in Fig. 4;

55 Fig. 6 is a top plan view of my improved heel attachment; and,

Fig. 7 is a perspective view illustrating one of the sheet metal detents which engage with the sides of the shoe heel.

Referring to these drawings in detail in 60 which similar reference characters correspond with similar parts throughout the several views, the attachment comprises a heel-plate 8, and an upstanding flange 9, a pair of detents 10, a releasing lever 11, a spring 12, and a pintle 13. In the present instance spurs or anti-slipping elements 14 are disclosed. But it is to be understood that this attachment may be secured to a skate runner 65 (not shown) or any other device which it is 70 desirable to attach to the heel of the shoe.

The heel-plate 8 and flange 9 may be either formed integrally or secured together so as to form a unitary structure, and the flange 9 is preferably U-shaped so as to conform to the contour of a shoe heel, the rear portion being semi-circular, the front portion 15 being plane or rectilinear and the top portion being wired at 16 so as to add strength and rigidity to the same. The 80 front portion 15 has its middle portion considerably lower than its ends and these ends are apertured for the reception of corresponding ends of the lever 11, and the corresponding ends of the lever 11 extend 85 through the apertured front part 15 and are each formed with a head 17 which prevents disengagement of the lever 11 from the portion 15.

Two opposite portions of the flange or 90 wall 9 are apertured at 18 for the reception of pairs of apertured ears 19 which are formed on the detents 10. These apertured ears are preferably formed by curving the outer ends of the ears 19 into cylindrical 95 form so as to snugly fit around the pintle 13. The apertures 18 are preferably of a size sufficient to allow the cylindrical ends of the ears 19 to be passed therethrough so that these ears may be formed with the cylindrical ends and thereafter passed through the apertures, for convenience in assembling the device. The pintle 13, in the present embodiment does not constitute a pivot, but serves as means for preventing disengagement of the detents 10 from the apertures 18. 100 These detents are supported in the apertures by the portion 20 of the ears, while the edge portions 21, 22 and 23 fit snugly against the inner surfaces of the flange or wall 9. By 110 this construction, the maximum strength and effectiveness of the detents 10 are ob-

tained. The detents extend inward and downward toward the heel-plate 8 when in their operative position, although they may be substantially horizontal when in the in-
5 operative position shown in Figs. 2 and 3, being held in this position by means of the spring 12 which is preferably a compound spring; that is, it practically consists of two springs, one for each of the detents 10, and
10 this compound spring has its middle portion bowed or semi-circular, as shown in Fig. 6, and this semi-circular portion conforms to the semi-circular inner and lower surface of the wall 9. The other portions,
15 however, push upward against the detents 10 and cause their relatively sharp edges 24 to press against the sides of the shoe heel. It will be seen, therefore, that any tendency to remove the shoe heel from the plate, or
20 the plate from the shoe heel, increases the tendency of the detents to grip the shoe heel and prevent the removal thereof from the attachment.

The lever or releasing member 11 extends
25 rearward from its fulcrum 17, over the plates or detents 10, and out through two apertures or slots 25 in the rear portion of the wall 9. The lever 11 is preferably formed of stout and comparatively rigid
30 wire, and its middle portion is formed with a loop 26 which may constitute a manipulative element or pedal which may be depressed for swinging the lever 11 downward in the slots 25 and thereby depressing the
35 detents 10 so as to disengage them from the shoe heel, and upon their disengagement, the device is very quickly and easily detached by simply raising the shoe heel or lowering the attachment.

40 Although I have described this embodiment of my invention very specifically, it is not intended to limit my invention to these exact details of construction and arrangement of parts, but my invention may be
45 slightly changed within the scope of the in-

vention idea disclosed in the foregoing description and following claims.

What I claim as my invention is:

1. A shoe-heel attachment comprising a heel-plate, a supporting element extending up from the margin of said heel-plate, a detent swingably mounted on said supporting element and inclined toward said plate, means co-operative with said detent for engaging a shoe heel and holding it on said heel-plate, and means for swinging said detent downward out of shoe-heel-engaging position.

2. A shoe-heel attachment comprising a heel-plate, an apertured flange extending up from the margin of said heel-plate, a detent swingably mounted on said flange and inclined toward said heel-plate, means co-operative with said detent for engaging with a shoe-heel and holding it on said heel-plate, and a lever fulcrumed in said flange and extending through an aperture thereof to a point of easy access for operation by the user, the intermediate part of said levers being positioned to bear against said detent so as to disengage the latter from the shoe-
60 heel.

3. A shoe-heel attachment comprising a plate, an apertured flange extending up from the margin of said heel-plate, a sheet metal heel-engaging element formed with ears having aligned apertures and extending through certain apertures of said flange, a pintle extending through the apertures of said ears exteriorly of the apertures of said flange, and means co-operative with said heel engaging element to hold a shoe-heel in engagement with said heel-plate.

In testimony whereof I have hereunto set my hand in the presence of two subscribing witnesses.

GEORGE W. BERRY.
